FIG. 4.

Henry H. Ponton, Inventor

By Mason Fennick Lawrence,

Attorneys

UNITED STATES PATENT OFFICE.

HENRY H. PONTON, OF GOLIAD, TEXAS.

WRENCH.

1,197,661.

Specification of Letters Patent. Patented Sept. 12, 1916.

Application filed January 11, 1916. Serial No. 71,570.

To all whom it may concern:

Be it known that I, HENRY H. PONTON, a citizen of the United States, residing at Goliad, in the county of Goliad and State of Texas, have invented certain new and useful Improvements in Wrenches; and I do hereby declare the following to be a full, clear, and exact description of the invention, such as will enable others skilled in the art to 10 which it appertains to make and use the same.

This invention relates to wrenches, and more especially to those having a pivoted outer jaw swinging around a fixed center or fulcrum; and one of the objects of the same 15 is to produce a wrench of this general character capable of gripping nuts or other angular articles between two of its flat faces which are brought into parallelism at various points so as to adapt the tool to the size 20 of nut being gripped; and this capability is inherent to the wrench whether the nut is to be turned on or off, or whether the article is to be turned to the right or to the left.

Another object of the invention is to utilize the same pivoted or swinging jaw and its face, in conjunction with another part of the rigid jaw for gripping round articles of 25 various sizes.

These objects are carried out by constructing the wrench in the manner specifically described and claimed below and as shown in the drawings wherein:

Figure 1 is a side elevation of this wrench, 30 showing its parts in full lines as gripping a square nut of moderate size and in dotted lines as gripping a large nut, and the right end of this view has been utilized to illustrate a socket wrench which may be formed in the rear end of the handle. Fig. 2 is a side elevation similar to Fig. 1, showing the pivoted jaw adjusted so as to grip a hexagonal nut. Fig. 3 is a similar side elevation showing the pivoted jaw swung past the tip 35 of the rigid jaw and illustrating the wrench as gripping a round article. Fig. 4 is a perspective view of the front end of the wrench with the parts standing about as seen in Fig. 3, but showing that the rigid jaw is in dupli- 40 cate.

Broadly speaking this tool comprises a staff or handle H whose front end is enlarged into a head which serves as the rigid jaw R, and whose rear end may carry or be

formed into some other tool such as a socket 55 wrench S. The head is forked as shown at F so that the working faces of the rigid jaw are duplicated, and between the fork arms on a pin or bolt B is pivoted the swinging or pivoted jaw P whose working face is 60 preferably in duplicate so that it will co-act with either working face of the rigid jaw. The various parts are preferably made of metal, but the materials, the sizes and proportions, and the exact details of construction 65 except as hereinafter specified, are not essential. As the working faces of the duplicate rigid jaws are alike, a description of one will suffice.

The front or outer edge of the rigid jaw is 70 formed on a practically straight line from the point 1 to the point 2, which line is oblique to the length of the handle H; and at the point 2 this line merges into a parabola which is continued to the point 3 opposite the tip 4 of the jaw. The parabolic edge is cut into a number of steps as shown, each having a face 5 and a riser 6. The rear edge of the rigid jaw is slightly curved and is provided with a number of teeth or serrations 9. The pivoted jaw P has its inner end 10 rounded where it stands between the arms of the fork F, and this end is pivotally mounted on the bolt B as best seen in Fig. 3. From the extremities of this inner end upper 80 and lower arms 11 and 12 extend outward in substantial parallelism with each other, and these arms are rigidly and preferably integrally connected at their outer ends by a head 13 which is somewhat wider than the 85 arms so as to form two faces 15 standing respectively opposite to the working edges of the rigid jaw. As these faces are alike, a description of one will suffice. Each face is 90 straight but slightly oblique to the length 95 of the arms 11 and 12, and therefore the face is tangential to an arc 16 struck around the center B, intersecting the face 15 at the point 17 and intersecting the parabola at said point 3. The construction is therefore 100 such that the pivoted jaw may be swung up so that its face will coact with certain of the faces on the outer edge of the rigid jaw to grasp angular work as seen in Figs. 1 and 2, or it may be swung down and round work 105 passed through its acute angle 18 and engaged by the teeth or serrations 9 on the rear edge of the rigid jaw as seen in Fig. 3.

In this illustration, when the handle H is moved as shown by the arrow the round piece of work would be turned to the left. In Figs. 1 and 2 when the handle is moved as shown by the arrows, the nuts would be turned to the right.

It will be obvious without further description that in order to turn either kind of work in the opposite direction, the 10 wrench must be reversed from the positions shown, and this explains the duplication of the rigid jaw by forking the head as stated.

While it might be possible to provide the outer edge of the rigid jaw with ordinary 15 serrations, and also serrate the opposed face of the head of the pivoted jaw as has heretofore been done, I find that the grip of a wrench so made is not sufficiently strong on most nuts to set them up tight or to start 20 them off their bolts when rusted in place. In order to accomplish this end, I therefore form the outer edge of the rigid jaw in rather liberal steps whose treads or faces 5 from the point 2 downward to the point 4 25 are farther and farther from the center B, but ever placed on lines truly parallel to the face 15 of the pivoted jaw; and by employing the proper tangent to the face 15 and the proper inclination to the parabola, I can 30 adapt the wrench for use on nuts of several sizes, and possible for use on hexagonal nuts as shown in the drawings. When the jaw P is swung upward to its limit as seen in 35 dotted lines in Fig. 1, a large nut will be received between the flat face 1-2 of the jaw R and the flat face 15 of the jaw P. As the pivoted jaw is moved down, its face 40 moves out of parallelism with said flat face, and as the steps are cut in a parabola which approaches and finally intersects the arc 16, 45 the inclination of their flat faces 5 must be progressive in order that they shall ever be parallel with that portion of the face 15 directly opposite when a nut is grasped between them. If the nut be such that its corner can pass into the angle between the face 5 and the riser 6, the grasp of the wrench is powerful—especially with a hexagonal nut as shown in Fig. 2. It is even possible 50 that the coaction of the face of any step with the face 15 may occur before these faces come into strict parallelism, and yet the grasp of the wrench when its handle is moved as shown by the arrow will be sufficient 55 to turn the nut. The same remarks apply when the wrench is reversed and employed for unscrewing the nut.

Ordinarily a nut stands at the end of its bolt, but if the latter should project it could 60 well be passed through the opening between the arms 11 and 12 of the pivoted jaw, as seen from Fig. 1. Round or irregular work such as a pipe is passed completely through 65 the opening in the pivoted jaw, the latter being swung downward as seen in Fig. 3.

The angularity of the head 13 to the arm 12 now becomes important, because the oblique serrated face 9 throws the work into the acute angle 18 when the handle is moved in the direction of the arrow in this view. Here 70 again the pipe could be turned in the other direction by reversing the wrench.

What I claim is:

1. A wrench comprising a handle; a rigid jaw at one end of the same having a perforation, the front edge of the jaw being struck on a straight line oblique to the length of the handle and merging into a parabola around said perforation, said parabola being cut in steps with faces of progressive inclination; a pin through said perforation; and a pivoted jaw having an inner end mounted on said pin, arms projecting thence outward, and a head extending obliquely across their outer ends and having its inner faces tangential to an arc around said pin. 75

2. A wrench comprising a handle; a forked rigid jaw at one end of the same having perforations through the fork-arms, the front edge of the jaw being struck on a parabola around said perforations, said parabola being cut in steps with faces of progressive inclination; a pin through said perforations; and a pivoted jaw having an inner end mounted on said pin within the fork, substantially parallel arms projecting thence outward, and a head wider than said arms, connecting their outer ends, and having its inner faces tangential to an arc around said pin. 90

3. A wrench comprising a handle; a forked rigid jaw at one end of the same having perforations through the fork-arms, the front edge of the jaw being struck on a parabola around said perforations, said parabola being cut in steps with faces of progressive inclination, and the rear edge of said jaw being curved and serrated; a pin through said perforations; and a pivoted jaw having an inner end mounted on said pin within the fork, arms projecting thence outward, and a head wider than said arms, extending across their outer ends, and having its inner faces tangential to an arc around said pin. 105

4. A wrench comprising a handle; a forked rigid jaw at one end of the same having perforations through the fork-arms, the front edge of the jaw being struck on a straight line oblique to the length of the handle and merging into a parabola around said perforations, said parabola being cut in steps with faces of progressive inclination, and the rear edge of said jaw being curved and serrated; a pin through said perforations; and a pivoted jaw having an inner end mounted on said pin within the fork, substantially parallel arms projecting thence outward, and a head wider than said arms, 125 130

extending obliquely across their outer ends, and having its inner faces tangential to an arc around said pin.

5. A wrench comprising a handle; a forked rigid jaw at one end of the same having its front edge struck on a straight line merging into a parabola, said parabola being cut in steps with faces of progressive

inclination, and the rear edge of said jaw being serrated; and a movable jaw having 10 its inner end pivoted within the fork and a head at its outer end extending over the edges of the fork-arms with its inner face tangential to an arc around said pivot.

In testimony whereof I affix my signature. 15
HENRY H. PONTON.
